Ira Fingerman,
By Joshua P. H. Potts
his Attorney.

UNITED STATES PATENT OFFICE.

IRA FINGERMAN, OF CHICAGO, ILLINOIS, ASSIGNOR TO UNIVERSAL LEATHER GOODS COMPANY, OF CHICAGO, ILLINOIS, A CORPORATION OF ILLINOIS.

POCKETBOOK AND VANITY CASE.

Application filed December 19, 1925. Serial No. 76,353.

My invention relates to a pocketbook and vanity case, and the same has for its main object the provision of an improved pocketbook and vanity case arrangement which will embody certain desired features of simplicity, efficiency and convenience and which will be economical to manufacture and durable in use.

Another object of my invention is the provision of an arrangement in which the pocketbook is made in the form of a flap covering designed to be buttoned or otherwise fastened about the vanity case.

Other objects will appear hereinafter.

15 The invention consists in the combinations and arrangements of parts hereinabove described and claimed.

The invention will be best understood by reference to the accompanying drawings forming a part of this specification, and in which,

Fig. 1 is a view in perspective of my improved article, showing it as it appears when closed.

25 Fig. 2 is a front perspective view, showing the flap covering unbuttoned and swung into open position;

Fig. 3 represents a cross section taken on the line 3—3 of Fig. 1;

30 Fig. 4 is another perspective view of the device when closed, this view, however, being taken so as to illustrate the back and bottom parts of the device; and,

Fig. 5 is a front view in perspective, 35 showing both the vanity case and the flap covering in open position.

In its preferred embodiment as illustrated in the accompanying drawings, my improved device comprises box body sections 6 and 7 which have their respective bottom sides or plates 8 and 9 connected by suitable hinges 10 for opening and closing movement. For securing the sections 6 and 7 together in closed relation, their respective top sides or plates 11 and 12 are provided with any suitable fasteners. In the exemplification herein shown, the top side or plate 12 is furnished with a catch fastener 13 which is adapted to cooperate with a keeper fastener 14 arranged upon the top side or plate 11. The interiors of the box-body sections 6 and 7 may be arranged, subdivided and finished in any manner suitable for containing the various toilet articles usually carried in vanity cases. In accord-

ance with an important feature of my present invention, I provide a pocketbook in the form of a flap covering 15 conformingly fitting the two box-body sections 6 and 7. In the construction shown, the flap 60 covering 15 has a portion 16 which is secured flat upon the front or face of the box section 6 and is coextensive therewith; a portion 17 which is secured to the bottom sides or plates 8 and 9 for covering the 65 same; a back portion 18 which covers the face of the box body section 7 and is connected thereto by suitably folded end pieces 19 arranged to produce a pocket 20 between the face of the box-body section 7 and the 70 covering portion 18. The flap covering also has a top portion 21 to cover the top sides or plates 11 and 12 as well as the fasteners thereon. The flap covering, furthermore, has a front portion 22 designed 75 to cover a mirror 23 which is suitably secured to the front of the box-body section 6 and over the front covering portion 16 thereon. Preferably and as shown, the front covering portion 22 is adapted to be 80 buttoned to the front covering portion 16 by means of a button 24 which is adapted to be engaged with a snapping action in the keeper 25. In the exemplification shown, the hinge members 10 are secured 85 to the bottom sides or plates 8 and 9 over the covering portion 17; but they may, in practice, be suitably arranged under said covering portion 17.

The flap covering 15 is made of leather, 90 imitation leather, or any suitable pliable material adapted readily to bend snugly about the corners of the box-body sections. The top portion 21 of the flap covering is equipped with a suitable handle 26 by 95 which to carry the device when the button 24 has been secured in its keeper 25. Obviously, the mirror may be used by simply unfastening the button 24 and raising up the flap covering. To use the mirror, therefore, the box sections need not be opened and the contents of the pocket 20 need not be disturbed.

In another condition of use, the box-body section 6 may be laid in horizontal position 105 and the companion section 7 moved vertically therefrom. Access, therefore, may be had to the interior of the vanity case without disturbing the contents of the pocket 20.

While I have illustrated and described 110

the preferred form of construction for carrying my invention into effect, this is capable of variation and modification without departing from the spirit of the invention.

5 I, therefore, do not wish to be limited to the precise details of construction set forth, but desire to avail myself of such variations and modifications as come within the scope of the appended claim.

10 Having described my invention, what I claim as new and desire to secure by Letters Patent is:

In a device of the character described, the combination of two hinge connected 15 box-body sections, each consisting of side panels with projecting retaining walls; said sections being arranged to insure the

meeting of their retaining walls to provide an interior space enclosed all around; a single covering of a length to extend 20 entirely around said sections and well beyond its point of beginning; said covering including a portion overlying the side panel of one section and fixed stationary thereto; connections connecting the side panel of the 25 other of said sections with said covering and therewith providing a pocket; a portion of said covering extending beyond said pocket, constituting a flap; and means for securing said flap to the stationary portion 30 of said covering.

In testimony whereof I have signed my name to this specification.

IRA FINGERMAN.
